JOHN MOSMANN, OF NORTH BERGEN, NEW JERSEY

TRIMMING FOR DRESSES AND THE LIKE

Application filed March 30, 1932. Serial No. 601,926.

This invention relates to improvements in trimmings especially adapted for application to dresses and other articles of feminine apparel and has particular reference to a trimming made of embroidery which is used to edge the necklines, collars, cuffs and the like of garments.

An object of the invention is to provide an improved trimming having a double scalloped edge effect and which is so constructed that it may be applied to curved edges of different portions of a garment and stitched thereto in perfectly flat condition.

The above and other objects will appear more clearly from the following detailed description when taken in connection with the accompanying drawing which illustrates a preferred embodiment of the inventive idea.

In the drawing:

Figure 1 is a fragmentary plan view of a trimming constructed in accordance with the invention and showing the same before the folding operation which precedes the actual stitching of the trimming to a garment.

Figure 2 is a similar view illustrating the trimming folded, and

Figure 3 is a fragmentary elevation showing the application of the trimming to the neckline of a garment.

The present trimming is preferably made of embroidery but it will be understood that other material may be used without departing from the spirit or scope of the invention.

The strip constituting the trimming is formed, as shown in Fig. 1, in a continuous length and constitutes a body portion which comprises a series of spaced panels 4. These panels are defined lengthwise thereof by the relatively heavy binding edges 5 which extend in a diagonally transverse direction across the strip of material and the longitudinal borders of said body portion are similarly defined by the straight binding edges 6 and 7 to which the ends of the edges 5 are connected. Along the edge 7, there is also formed a scalloped edging 8 which constitutes one of the longitudinal edges of the trimming in its completed form, as will appear in the course of the description.

When forming the strip of trimming the

spaces between adjacent panels 4 which are defined by the edges 5 are filled in with the same material which constitutes the main portions of the panels and it becomes necessary to then remove the filling between said edges in order to separate the spaced panels one from another. The removal of said filling is usually accomplished entirely by the use of manually operated shears. To facilitate this removal operation to some extent, the space between adjacent edges 5 is widened intermediate the ends of the panels by forming opposed indentations 9 in said edges so that sufficient area between the latter is provided to enable a mechanically operated punch or like implement to be initially used in cutting out the filling contiguous to said indentations, after which the remainder of the filling may be manually removed as heretofore.

To apply a completed length of the trimming to a garment, said length is first folded longitudinally upon itself with the edges 6 and 7 in alinement so that the scalloped edging 8 projects from the folded body portion. The folding line of the trimming is coincident with the indentations 9 and, by reason of this and the diagonal arrangement of the edges 5, the latter will form a scalloped effect, as clearly shown in Figure 2, along the edge of the trimming opposite the scallop 8, thus providing the trimming with a scallop along both longitudinal edges. The scalloped effect along the edge opposite the edging 8 is enhanced by the indentations 9.

After the trimming has been folded as described it may be secured to a garment by stitching along the now contiguous edges 6 and 7. The trimming may be secured in position along a straight line or may be attached to a curved surface such as the neckline, cuffs or collar of a garment. The fact that the diagonally extending panels 4 are separated one from another enables the trimming to readily conform to the contour of and lie flatly against the curved surface or edge to which the same is attached, since the panels are permitted to separate along the edge of the trimming opposite the edging 8 as said trimming is laid against said surface. As shown in Figure 3, the trimming is applied

to the neckline of a garment and lies flatly thereagainst by reason of the fact that the individual panels 4 are permitted to spread apart along the free edge of the trimming, the amount of spread being in proportion 5 to the degree of curvature of the edge of said neckline. From this, it will be apparent that the trimming, when folded in the manner described, may be applied to any curved 10 edge or surface of a garment and will always lie flatly in position when stitched thereto.

What is claimed is:

1. As a new article of manufacture, a trimming comprising a body portion consisting of a plurality of spaced panels, and a scalloped edging extending along one longitudinal edge of said body portion, the latter being foldable longitudinally upon itself so that the line of fold will constitute the edge of the 15 trimming opposite said scalloped edging.
2. As a new article of manufacture, a trimming comprising a body portion consisting of a plurality of spaced panels extending diagonally and transversely of said body portion, and a scalloped edging along one longitudinal edge of said body portion, the latter being foldable upon itself so that the medial 20 portions of said panels will constitute another scalloped edge for the trimming opposite the first named edging.
3. As a new article of manufacture, a trimming comprising a body portion consisting of a plurality of spaced panels extending diagonally and transversely of said body portion, the edges of adjacent panels being provided with opposed indentations therein, and a scalloped edging extending along one longitudinal edge of said body portion, the latter being folded upon itself on a line coincident 25 with said indentations to form another scalloped edge for the trimming opposite said scalloped edging.

In testimony whereof I have affixed my signature.

45 JOHN MOSMANN.
